UNITED STATES PATENT OFFICE

135,264

DESIGN FOR A PLAQUE BASE OR THE LIKE

Guy E. Gaston and Harold Stilwell, Baltimore, Md.

Application November 12, 1941, Serial No. 104,124

Term of patent 3½ years

To all whom it may concern:

Be it known that we, Guy E. Gaston and Harold Stilwell, citizens of the United States, residing at the city of Baltimore, in the State of Maryland, have invented a new, original, and ornamental Design for a Plaque Base or the like, of which the following is a specification, reference being had to the accompanying drawing, forming part thereof.

Fig. 1 is a front or face view slightly in perspective of a plaque base showing our new design.

Fig. 2 is a lower edge view.

The essential features of our design reside in a plaque base substantially of the configuration shown, having a substantially circular opening near and below a central apex, the front surface of the base being divided by substantially straight parallel lines into the respective areas shown within marginal lines on Fig. 1.

We claim:

The ornamental design for a plaque base or the like, substantially as shown and described.

GUY E. GASTON.
HAROLD STILWELL.
